(57) **CLAIM**

The ornamental design for an eye shield, as shown and described.

DESCRIPTION

FIG. 1 is a front top perspective view of the eye shield, showing my new design;

FIG. 2 is a rear top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof, with the bottom plan view being a mirror image thereof; and,

FIG. 8 is another front top perspective view thereof, showing the eye shield in a position of use on a human figure drawn in broken lines.

The broken line showing of a human in FIG. 8 depicts environment and forms no part of the claimed design.

1 Claim, 3 Drawing Sheets
